Edward J. Pennington, Inventor
by M. W. J. Ward, Attorney.

UNITED STATES PATENT OFFICE.

EDWARD J. PENNINGTON, OF LONDON, ENGLAND.

ASSEMBLING-FRAME FOR STEAM-BOILERS.

SPECIFICATION forming part of Letters Patent No. 694,413, dated March 4, 1902.

Application filed June 10, 1901. Serial No. 64,033. (No model.)

To all whom it may concern:

Be it known that I, EDWARD J. PENNINGTON, a citizen of the United States, residing at London, England, have invented new and useful Improvements in Assembling-Frames for Use in the Building of Steam-Boilers, &c., of which the following is a specification.

My invention consists of an assembling-frame to facilitate the building up of a tubular boiler, condenser, or other structure, substantially as is described in my application, Serial No. 64,036, filed June 10, 1901.

In the accompanying drawings, Figure 1 is a perspective view of my improvement. Fig. 2 is an elevation, partly in section, illustrating the use of the invention.

Similar numerals of reference indicate similar parts in the respective figures.

I take a frame 1, made of light metal, cylindrical in shape and of the required diameter and length—say, for illustration, five inches internal diameter by eighteen inches in length. At one end of this cylinder 1—say about three-eighths inches inward from its edge—the internal diameter is reduced about one-eighth inch. This may be done by compression, hydraulically or otherwise, by spinning over in a lathe, or by swaging. I then cut two screw-threads 2 3, one at each end of the cylinder, by means of two taps, both mounted on one drill-spindle. The two taper taps have similar gage, and the threads are cut simultaneously at both ends of the cylinder, though the thread 2 in the wall of the cylinder at the end where the internal diameter has been reduced one-eighth inch is of course smaller in diameter than the thread 3 at the other end, where the internal diameter of the cylinder still remains five inches. I then cut away a

large portion of the walls of the cylinder, as shown at 4, sufficient material being left of the walls to keep the two ends firmly braced. Into the ends of the cylinder 1 I now screw the two heads of my boiler, (constructed as described in my said application, Serial No. 64,036,) the outer periphery of each being threaded with a properly-pitched screw, so as to engage in the thread cut at that end of the cylinder which is of corresponding diameter to the particular head, one head being five inches diameter and the other four and seven-eighths inches. The two heads 5 (see Fig. 2) are now in position, locked firmly in their

places and at the exact distance apart at which they are later to be permanently fixed 55 in the boiler-shell. I now proceed to pass from head to head through holes which have been previously made small tubes 6—say forty in number—of one-half inch diameter, and I fix the tubes in place by beading, spinning, or swaging over the ends which protrude through each head about one-eighth inch, so as to form a joint which will be watertight.

The object in view in cutting away the walls 65 of the cylinder 1 on two sides, leaving only as much standing as will firmly brace the threaded ends, will now be seen—viz., to enable the workman to more quickly and easily pass through and adjust the small tubes. 70

Instead of making the frame out of a cylinder two rings of slightly differing diameters, corresponding to the two ends of the cylinder described, and with screw-threads made to engage the respective heads, might be braced 75 and held rigidly apart at the correct distance by three or four pillars. Having secured all the small tubes 6 to the heads 5, I now unlock these heads and tubes at one operation as an entirety from the cylinder or frame 1 80 by unscrewing the heads, which can be done by holding them and the tubes in a vise and revolving and thus unscrewing the frame. The heads and tubes may then be withdrawn from that end of the frame which is of larger 85 diameter and afterward inserted in the boiler-shell, which is of differing diameter at its respective ends, is tapped with screw-threads, and in other necessary ways conforms to the temporary building or assembling frame in which the heads and tubes were 90 first assembled.

I claim—

An assembling-frame for use in constructing tubular cylindrical boilers, condensers, 95 or the like, consisting of an open frame combined with concentric cylindrical ends of different internal diameters, said heads being cut with equally-pitched threads, substantially as set forth.

In testimony whereof I affix my signature in presence of two witnesses.

EDWARD J. PENNINGTON.
